[57] **CLAIM**

The ornamental design for a rack for storing, singularizing and teeing golf balls, as shown and described.

DESCRIPTION

FIG. 1 is a right front perspective view of a rack for storing, singularizing and teeing golf balls, showing my new design;

FIG. 2 is a left front perspective view thereof, showing the pivoted track arm in lowered position;

FIG. 3 is a front elevational view thereof;

FIG. 4 is a rear elevational view thereof;

FIG. 5 is an elevational view of the left side thereof;

FIG. 6 is an elevational view of the right side thereof;

FIG. 7 is a top plan view thereof; and,

FIG. 8 is a bottom plan view thereof.

The showing of a golf ball and a fixed golf tee in broken line in FIGS. 2 and 3 are for environmental purposes only and form no part of the design.
